LEONARD J. MARSHALL, OF WESTWOOD, NEW JERSEY, ASSIGNOR TO INTERNATIONAL COMBUSTION ENGINEERING CORPORATION, OF NEW YORK, N. Y., A CORPORATION OF DELAWARE

APPARATUS FOR REHEATING STEAM FOR USE IN TURBINES

Application filed May 31, 1928. Serial No. 281,825.

This invention relates to improvements in the art of reheating steam in boilers and particularly to reheating interstage steam of prime movers.

5 In this art it is customary to take steam for a turbine from two or more boilers and to return steam from a certain stage of the turbine, or from the exhaust of a high pressure turbine, to reheaters located in the path of the gases in one or all of the several boilers 10 cooperating with the turbines, or to separately heated reheaters, and from thence to pass the reheated steam to the succeeding stage of the turbine or to the low pressure 15 turbine which cooperated with the high pressure turbine.

In order that this may be done in a manner to ensure low maintenance and to obviate possible damage to the turbine, it is important 20 that an even temperature of steam obtains in the turbine at all ratings of the boiler.

In the case of two boilers with reheat in each boiler, it has heretofore been the practice, in order to meet the above conditions, to connect the reheaters in parallel and to provide means for dividing the steam passing to the reheat in proportion to the load being carried by each 30 boiler. Apparatus known for this purpose comprises thermostatically controlled valve devices of a complicated nature.

I propose to obviate the operating difficulties of maintaining a constant reheat by means of a reheat in the path of the gases in one of the several boilers employed, or in a separately fired reheat, or by employing valve devices of any description for the purposes above set forth, and it is, therefore, one 40 of the objects of my invention to provide an apparatus for reheating steam for turbines or engines by means of which the degree of heat leaving the reheat of two or more boilers supplying steam to the units is maintained substantially uniform, although the ratings of the individual boilers may vary.

More specifically stated, it is an object of my invention in apparatus of the class described to serially connect the reheat of two or more boilers so that a substantially

uniform degree of superheat leaving the reheaters is obtained at all ratings of the boilers.

It is to be understood that fluids other than steam may be reheated by my method and for other purposes than that described herein. The method may be used in cooperation with either the convection, radiant heat or other type of superheater and any combination of them.

How the foregoing, together with such other objects and advantages as may herein-after appear, or are incident to my invention are realized is illustrated in preferred form in the accompanying drawing, wherein—

The figure is a diagrammatic view illustrating my invention.

In the drawing I have diagrammatically shown two high pressure boilers at A and B, say, for example, a boiler having some pressure above 450 lbs., and a two-stage turbine at C. The boiler A is equipped with a superheater 2 and a reheat 3, and the boiler B is equipped with a superheater 4 and a reheat 5. The turbine C is divided into a high pressure end 6 and a low pressure end 7 in a well known manner, or the two ends may be separate units as is often the case.

Steam from the superheater 2 of the boiler A and from the superheater 4 of the boiler B leads in parallel by means of steam lines 8 and 9, into the main steam line 10, which, in turn, leads to the high pressure end 6 of the turbine C. After the steam has expanded in this end to the stage where resuperheating becomes desirable, it is led off from this stage of the turbine by means of a pipe line 11 and is passed serially through the reheat of the boilers and returned to the following stage of the turbine. In this instance the pipe 11 is connected to the reheat 5 of the boiler B, and this reheat is connected in series with the reheat 3 of the boiler A. A pipe line 12 connects the reheat 3 with the following stage in the low pressure end 7 of the turbine.

The reheat 3 and 5 are preferably of equal capacity and, owing to their connection in series, they will adjust themselves in their heat output to the variations of performance of their respective boilers. Thus, with a con-

stant total output of all boilers, should one boiler work at a higher or lower rating than the others, the superheaters will likewise work at proportionately higher or lower ratings, and hence adjustment of the reheat-
5 ers to the relative decrease or increase in ratings of their boilers is effected, and the sum of the superheats of the individual re-
heaters, owing to their serial connection, will
10 remain substantially constant.

From the foregoing it will be seen that I have provided a very simple and effective apparatus for reheating steam for use in turbines in which two or more boilers are em-
15 ployed, by means of which an even tempera-
ture of reheated steam obtains in the turbine at all ratings of the boilers without the neces-
sity of employing complicated mechanisms for distributing the steam to be reheated to
20 the boilers proportionately to the amount of work being done by the boilers.

I claim:—

1. In combination, a plurality of boilers, a multiple stage prime mover, means for lead-
25 ing high pressure fluid from said boilers to the high pressure stage of said prime mover, a fluid reheat-
er in each of different boilers, said reheat-
ers being connected in series, means for leading the fluid from a stage of
30 the prime mover to said serially connected re-
heat-
ers, and means for leading the reheated fluid from said serially connected reheat-
ers to the stage following said stage.

2. In combination, a plurality of boilers,
35 each one of which is provided with a super-
heater, a multi-stage turbine, a main fluid line leading to the high pressure stage of the turbine, means for supplying working fluid to said main steam line from said superheat-
40 ers in parallel, a reheat-
er for each of different boilers, means for connecting said reheat-
ers in series, means for leading the fluid from a lower stage of the turbine to said reheat-
ers, and means for leading reheated fluid from
45 said reheat-
ers to the stage following said lower stage.

In testimony whereof I have hereunto signed my name.

LEONARD J. MARSHALL.
